(57) **CLAIM**

The ornamental design for a stock for a firearm or the like as shown and described.

DESCRIPTION

FIG. 1 is a perspective view of an embodiment of a stock for a firearm or the like showing the new design, shown in a collapsed position of use;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and

FIG. 9 is another perspective view thereof, shown with a firearm.

FIG. 10 is a perspective view of another embodiment of a stock for a firearm or the like showing the new design, shown in an expanded position of use;

FIG. 11 is another perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is another perspective view thereof, shown with a firearm.

The broken lines illustrate features of the stock for a firearm or the like that form no part of the claimed design. The firearms shown in FIGS. 9 and 18 illustrate environment and form no part of the claimed design.

1 Claim, 14 Drawing Sheets
